FIG. 2.

UNITED STATES PATENT OFFICE.

EUGENE R. KNAPP, OF BROOKLINE, MASSACHUSETTS, ASSIGNOR TO
HENRY DE FORD, OF BROOKLINE, MASSACHUSETTS.

INDIRECT-HEATING SYSTEM.

SPECIFICATION forming part of Letters Patent No. 784,110, dated March 7, 1905.

Application filed April 10, 1903. Serial No. 151,946.

To all whom it may concern:

Be it known that I, EUGENE R. KNAPP, a citizen of the United States, residing at Brookline, in the county of Norfolk and State of Massachusetts, have invented certain new and useful Improvements in Indirect-Heating Systems, of which the following is a specification, reference being had therein to the accompanying drawings.

10. Figure 1 is a vertical section showing a series of compartments which represent rooms in a building provided with my improved indirect-heating system. Fig. 2 is a horizontal plan view, partly in section, at line 2 2 of Fig. 1, this view showing the steam or hot-water feed pipe more clearly than it is indicated in Fig. 1 and also indicating the preferred arrangement of the outside-air conduits, the outer ends of which extend without the building in 15 four different directions—for example, north, east, south, and west—and intersecting at their communication with the air-box supply-conduit, fans being shown in the air-conduits. Fig. 3 is a detailed view, partly in section, at line 3 3 of Fig. 2, and shows one 20 form of mechanical contrivance whereby the valve of an uptake and the valve of its return-pipe may be operated from a distance. Fig. 4 is a detail view, partly in section, showing 25 one form of a valve-adjusting device; and Fig. 5 is a detail view, partly in section, showing one mechanical mode of opening and closing an air-gate from a distance. Fig. 6 is a 30 detail view of the flanged coupling construction, whereby the uptakes and their returns are detachably connected.

The main objects of my invention are, first, to supply continuously to rooms fresh outside air which is warmed from near its intake 35 into the building until it is discharged into the rooms, utilizing in so doing the heat of returning steam or hot water to preheat the air admitted to an air-box containing the direct-heating pipe; second, to eliminate, at least in the second story and stories thereabove, the use of radiators and numerous valve parts commonly used therewith; third, to distribute warmed air to the various rooms with a minimum heating of the walls; fourth, to utilize the

chimney construction by building contiguously thereto the upwardly-extending air-flues thus making my system as economical of room as possible; fifth, to provide means whereby the occupant of an upper story may regulate the heat admitted to a room by means accessible within the room, and, sixth, to provide means whereby in case of leaks in the water or steam pipes, which extend upwardly within the upwardly-extending air-flues, the pipes may be readily removed without taking up floors or breaking into side walls or ceilings.

In the drawings, which illustrate one of various embodiments of my invention, the form shown being on the whole the best now known to me, A represents the basement of the building; A', the basement-floor; A², the ground or first floor; A³, the second floor; A⁴, the third floor.

B indicates the chimney construction, and b upwardly-extending air-flues, which are preferably built in at the chimney sides.

In the present form of my invention I have shown in the ground-floor rooms A² ordinary registers a' and valve-handles a² for the radiators A⁵, which are in the air-box D and beneath the first floor A². In installations of the system I prefer for the first-floor rooms this old and well-known arrangement of radiators, valves, and registers, although the features of my invention are as applicable to the first-story rooms, if desired, as they are to the second and thereabove stories.

Either steam or hot water from any suitable source located either within or without the building may be used; but I will describe it with reference to the use of steam.

1 is the steam-feed pipe to the system and may be supposed to come from a boiler outside the building. Pipe 1 communicates at 2 with a horizontal steam-distributing pipe 3 within air-box D, which is secured to the basement-ceiling in any suitable manner. The extremities of pipe 3 are provided with downwardly-extending return-bends 4, which communicate with the return steam-pipe 5 within air-box D below pipe 3. Radiators A⁵ are shown on pipe 3, there being one valve a² at each end of a radiator A⁵. Return steam-pipe

5 in the air-box communicates with a vertical return-steam-pipe section 6, which communicates with a horizontal return steam-pipe 7 within an outside-air conduit F.

5 In the present construction two auxiliary return steam-pipes 8 are shown, the shorter arms communicating at 9 with pipe 5 and the longer arms extending parallel with pipes 3 and 5 and being below pipe 3. Each upwardly-extending air-flue b contains within its walls at a distance from the walls an upwardly-extending uptake 10, the lower end of which is in communication with the steam-supply pipe 3. Each uptake is carried upward within an air-flue b into the desired room on the second story or some story thereabove, and each uptake is in communication with a return steam-pipe 11, also within the air-flue and at a distance from the walls thereof, the lower end of pipe 11 communicating with the longer arm of the return-pipe 8. The upper ends of each uptake 10 and its return 11 are connected by a flanged coupling 12, the flanges being bolted together by removable bolts 13. The uptakes 10 and returns 11 are made of pipe-sections which are conveniently six or eight feet long and coupled together by removable couplings 14. An air-pipe 15, frequently called an "air-valve," connects each flanged coupling 12 with a return steam-pipe (in the present instance with 8) in order to permit a free circulation of steam or water in the uptakes or returns.

As best seen in Fig. 3, each uptake is provided at its foot with a regulating-valve 16, and each return-pipe 11 is provided with a similar valve 16. Any desired kind of shut-off or regulating valve may be used in lieu of the form of valve shown, wherein each valve 16 has its stem provided with a crank-arm 17. To the outer end of each crank-arm 17 a vertical rod 18 is attached and carried upwardly through the air-flue, being provided at its upper end in this particular instance with a flanged post 19, which passes through a bearing 20 in the upper end of the air-flue. An adjusting-nut 21 is mounted on said post 19 and bears against the upper surface of the bearing 20. Post 19 is provided with a lengthwise groove 22, which receives a suitable projection from the bearing 20, so that when nut 21 is turned to move the rod 18 in either direction to regulate the valve 16 the post 19 will not be rotated. This is merely one of a great number of obvious mechanical ways of moving a valve 16. The bottom of each air-flue b is provided with an air-gate 30, which may be of any desired construction, but which for the purposes of convenience is here shown in the form of an old and well-known register made up of a series of pivoted slats 31, which are connected to a slide 32, provided with the usual ear 33. On a pivot 34 I mount an L-shaped lever 35, having a lengthwise slot 36, which receives a pin 37 from the ear 33. To the other end of the L-shaped lever 35 I

attach a rod 38, which extends upwardly to an adjusting-post 39, provided with an adjusting-nut 40, which works against the bearing 20 precisely as in the case of the adjusting mechanism for the valves 16. The adjusting-nuts 40 are, like the adjusting-nuts 21, accessible to the occupant of the story into which the particular air-flue extends. By proper manipulation of the adjusting-nuts 40 air is cut off or admitted to the air-flues. 75

The under sides of the air-box D are provided with suitable doors d or other covers for openings in the under side of the air-box, the openings being directly below the air-flues. If a leak occurs in an uptake or in its return-pipe or in the air-pipe 15, which are also made up of coupled sections, the door d thereunder may be opened and the air-gate 30 removed. The flanged couplings 12 being loosened from the uptake and its return-pipe and the uptake or its return being then disconnected from the pipes 3 and 5, the uptake or its return, or both, may be drawn down from within the air-flue into the basement. If the length of the uptake or its return-pipe be greater than the height of the basement, the couplings 14 may be uncoupled and the uptake and its return-pipe removed in sections, and so, also, as to the air-pipe 15. This provision for withdrawing the pipes from the air-flues 8 downwardly is important, as it obviates the necessity of tearing up floors or breaking into side walls of the rooms in order to repair the pipes when a leak occurs. 90

A serious objection has been long commonly experienced in heating systems because of a practically direct contact of the steam or hot-water pipes with the walls of the building, the walls becoming so hot that considerable time has frequently been required for the rooms to cool off after the steam or hot water has been shut off. Expensive heat-insulating material, like asbestos, has been used to prevent this overheating of the walls, but without much success. In accordance with my plan the uptakes 10 and their return-pipes 11 are separated from the walls of the air-flues, and as the air travels up through the air-flues in the space between the inner walls of the flues and the outer walls of the uptakes and return-pipes the heating of the walls of the building is minimized and heat is saved. The air-flues may be made of any suitable material; but I prefer to make them of expanded-metal lathing, to be plastered within, and the flues to be constructed as the building progresses; but ordinary chimney-flue linings may be used. 115

Each air-conduit F opens to the outside of the building, so as to provide fresh air to the air-box D through the air-conduits F and the air-box supply-conduit f, which connects the air-box and outside-air conduits F. Near the outer end of each conduit F, I mount a suitable fan G, preferably an electric fan, where-by air is continuously drawn through air-con- 120 125 130

duits F and forced through air-box supply-conduit f and into the air-box, whence it passes upwardly through the air-flues b and out into the rooms through the registers R. 5 It will be observed that the air so drawn in from without in its travel through the conduits F and air-box supply-conduit f is in contact with the return-pipe sections 6 and 7, so that the air taken in is continuously warmed 10 from near its intake until it is delivered through the registers R, being given a higher temperature than is given to it by the heat from the return-pipes 6 and 7 when it passes over the live-steam pipe 3 and the return-pipe 15 5 within the air-box D. In other words, I preheat the air for admission to the air-box and do the preheating by utilization of the heat of the return steam after it leaves the air-box. The utilization of the return steam 20 after it leaves the air-box to preheat the incoming air is an important economic feature of my system. In some indirect-heating systems, where the air is heated in hot-air reservoirs in basements and distributed by metal 25 conduits to various parts of the building, the air grows cooler and cooler until it is let out into the rooms. By my invention, on the contrary, the air from without is made hotter and hotter from the time it first contacts with the 30 return-pipe until its delivery into the rooms.

Heretofore it has been the practice in indirect-heating systems to have the outside-air-supply conduit F open on the outside of the building at its two ends on opposite sides of 35 the building; but I prefer, where possible, as in the case of detached dwelling-houses, to have four branches of the outside-air-supply conduit F, one branch opening northerly, another easterly, another southerly, and another 40 westerly, so that from whichever direction the wind blows fresh air may be more readily supplied.

In the present instance the four conduits F intersect at the foot of the conduit f, which 45 communicates with all the conduits. By the use of fans I avoid taking air from the windiest and coldest side of a building and may take the air from the warmest side. Even if a plurality of branches are installed it may 50 not be necessary to use them all; but this will depend somewhat on the size and location of the building. If preferred, a single air-supply conduit F, with or without a fan, may be used.

The air-conduits may supply any number 55 of upwardly-extending flues in various parts of the building. The air-flues need not necessarily be built at the chimney sides; but this location is generally economical of space. The steam-pipes 3 and 5 by suitable branches 60 may be connected with various other air-boxes in other parts of the building, and a branch, as from pipes 3 and 5, is indicated. I prefer to have the air-conduit F pass under the basement-floor, as shown, after it enters the building 65 for economizing room.

The upwardly-extending air-flues, with interior means for heating the current of air passing upwardly therethrough are important, for where walls of rooms are, as now, heated by contact with even insulated pipes the 70 rooms are kept uncomfortably hot and heat wasted, and frequently the walls are cracked and expensive wall papers injured in consequence of the excessive heat. The provision for the downward withdrawal of the heating-pipes from the air-flues in case of leaks is also of great economical importance, while the elimination of radiators and valves saves much expense of installing heating systems. Economy of installation, of repairs, and of heat 75 units are advantages of my invention, as also are the facts that fresh air is constantly supplied by it and injury to wall papers or decorations and to ceilings avoided when leaks occur, for the water or drip from leaks must 80 run down the uptakes or returns directly into the basement and not, as heretofore, run down the walls and work out in side walls and ceilings. It will be noticed, also, that the upwardly-extending air-flues serve as ventilating-flues. The advantage of having valve 85 and air-gate controllers accessible in the various rooms is obvious.

The air-gates or registers at the bottom of the air-flues are removable and are shown 90 held in place by clips 50. The chimney construction is indicated by B, there being in this instance two upwardly-extending air-flues on each side of the chimney. The chimney-walls make a good support for the air-flues, which can be readily built one against another, the innermost flues being along the upwardly-extending chimney sides, one set of air-flues 95 going to different rooms on the second floor and the other set to different rooms on the 100 third floor. Thus I indicate four rooms as being heated (and ventilated) from the four air-flues shown; but it will be understood that by constructing other air-flues at sides of the air-flues shown four other rooms on the second and third floors can be heated from such a stack of eight air-flues.

The steam-return pipe extends through the air-supply conduit, whereby the air is pre-heated by the return steam and the steam in the return-pipe is condensed, thereby increasing the circulation of steam through the system. This is new with me and results in marked economy of heat units. The pipes 8, 4, 6, and 7 constitute one form of steam-return main. The air-box D, conduit f, and outside-air conduits F constitute one form of air-supply chamber for the upwardly-extending air-flues.

Various changes can be made in the form 115 of the various parts which enter into the construction of my new system without departure from my invention.

What I claim is—

1. The combination with a plurality of 120

rooms, in a building, of an air-box; a plurality of air-flues communicating with the air-box, extending upwardly therefrom, and opening, one into one room and another into another room; a steam-distributing pipe in the air-box; a return steam-pipe communicating with the steam-distributing pipe; and a plurality of upwardly-extending steam-pipes, each communicating with the steam-distributing pipe; and severally extending upwardly within the air-flue; a plurality of downwardly-extending return steam-pipes communicating severally with said upwardly-extending steam-pipes, and all communicating with said return of the steam-distributing pipe; an air-conduit leading to the air-box; the upwardly-extending steam and return pipes being detachably connected together and to the steam-distributing pipe and to the return thereof, and withdrawable downwardly out of the air-flues; regulating-valves in the upwardly-extending steam-pipes; and means, accessible in each room, for opening and closing the regulating-valves with which the upwardly-extending steam-pipes are provided.

2. The combination with a plurality of rooms in a building of a plurality of upwardly-extending air-flues, each opening into a room, an upright steam-supply pipe and a therewith-connected downwardly-extending return-pipe 30 within each flue; a steam-distributing pipe communicating with said upright steam-supply pipes; a steam-return main connected with said downwardly-extending steam-return pipes and an air-chamber communicating with 35 and supplying air to said upwardly-extending air-flues; the steam-return pipe extending through the air-supply chamber, and thereby preheating the air by the return steam which, in the return-pipe, is condensed and increases 40 the circulation of the steam through the system.

In testimony whereof I affix my signature in presence of two witnesses.

EUGENE R. KNAPP.
